(57) **CLAIM**

The ornamental design for a memories booklet, as shown and described.

DESCRIPTION

FIG. 1 is a perspective view of a memories booklet in an open state showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view of the memories booklet in a closed state; and,

FIG. 9 is a front elevation view thereof.

The broken lines that are immediately adjacent to the claim represent the bounds of the claim and are not included in the claim, while all other broken lines are directed to environment; the broken lines form no part of the claimed design.
